TIE KNOT HOLDER

Severin B. Bankson, San Francisco, Calif.

Application March 24, 1943, Serial No. 480,394

6 Claims. (Cl. 2—153)

The present invention relates to improvements in a tie knot holder, and it consists of the combinations, constructions and arrangements hereinafter described and claimed.

An object of my invention is to provide a tie knot holder that is made of a flexible and transparent material and is adapted to act as a form for a tie knot so that it is not necessary for the wearer to pass the midportion of the tie around the back of the neck and then make the usual four-in-hand knot with the ends of the tie. The invention is a very simple one and comprises but two pieces: a flexible, transparent supporting body and a wire spring. The wire spring performs two functions: (1) providing a yielding body or form for the tie knot, and (2) securing the device to a collar button for supporting the device in proper place. The spring is so constructed that the portion engaging with the collar button acts as an additional spring extension for the portion that supports the tie knot.

Other objects and advantages will appear in the following specification, and the novel features of the device will be particularly pointed out in the appended claims.

My invention is illustrated in the accompanying drawing forming a part of this application, in which:

Figure 1 is a front elevation of the device;

Figure 2 is a side elevation;

Figures 3 and 4 illustrate how the tie is secured to the device to form a knot; and

Figure 5 is a section along the line 5—5 of Figure 4.

While I have shown only the preferred form of my invention, it should be understood that various changes or modifications may be made within the scope of the appended claims without departing from the spirit of the invention.

In carrying out my invention I provide a Y-shaped body member or holder, indicated generally at A. The body is formed of a transparent and flexible material and has two wings 1 and 2 that are adapted to be received in the sides of the collar, not shown. A depending portion 3 is integral with the wings 1 and 2 and supports a flexible wire, indicated generally at B. Figures 1 and 2 show the ends 4 and 5 of the wire passed through openings 6 and 7 in the member A, the wire ends 4 and 5 being crimped to contact with both the front and rear surfaces 8 and 9 of the body member A, see Figure 2. The wire has leaf spring portions 10 and 11 that extend from the ends 4 and 5 down to openings 12 and 13 provided in the depending portion 3. The leaf

springs 10 and 11 have their free ends passing through the openings 12 and 13 and a loop portion 14 is integral with the leaf springs 10 and 11 and extends along the rear face 9 of the member A. The openings 12 and 13 are about twice the diameter of the wire B.

Figure 1 illustrates the loop 14 as having a wide button receiving recess 15 and a smaller recess 16 at its top for receiving the shank of the collar button or the threads that secure the button to the collar. Since the openings 12 and 13 are about twice the diameter of the wire, they will permit the wire B to slide freely therethrough.

From the foregoing description of the various parts of the device, the operation thereof may be readily understood.

In Figures 3 and 4 I illustrate how a tie, indicated generally at C, can be secured to the device and form a permanent tie-knot. The tie is placed on the device so that the small end 17 of the tie hangs downwardly from the curved upper edge 18 of the body member A. The midportion of the tie is passed around in back of the wing 1, see Figure 3, and in front of the small tie end 17. Figure 4 illustrates how the large end 19 of the tie is passed around in back of the wing 2 and then is brought over the small end 17 and in back of the central portion 20 of the tie. When the two ends 17 and 19 are pulled downwardly, they will cause the central portion 20 of the tie to be pulled tightly around the tie portions that overlie the leaf springs 11. The result is the formation of a tie knot that closely resembles a standard four-in-hand knot. Figure 5 illustrates how the leaf springs 10 and 11 support the tie knot so as to give the central portion 20 the proper curvature to simulate a four-in-hand knot. The wire loop 15 and the smaller loop 16 extend in back of the tie portions that lie against the rear face 9 of the member A.

When the tie is once secured to the body member A, it need not be retied. The device with the tie can be placed in position in the collar with the wings 1 and 2 hidden by the sides of the collar, and the collar button received in the small recess 16 of the loop so as to support the device in proper position. Inasmuch as the wings 1 and 2 are transparent, they will be invisible should any portion of them be uncovered by the sides of the collar. Moreover the flexible nature of the wings permits them to curve and conform to the curve in the collar without creating any bulge in the front of the collar. The tie knot will be resiliently supported by the leaf springs 10 and 11 and added resiliency will be afforded to the leaf

springs 11 by the fact that the loop portion 14 is integral with the leaf springs and has its reduced end 16 anchored to the collar button. The member A can be of different shapes and sizes to take care of collars of different types. In like manner the loop 14 can have its small recess 16 disposed at different heights to accommodate the device to a particular collar. It will be noted in Figure 1 that the wire has portions 21 and 22 bent outwardly, these portions being disposed immediately in back of the rear face 9 of the member A. The portions provide a double function in that they make a large loop 14 that will receive a collar button and they also act as a stop against the rear face 9 to limit the outward swinging of the leaf springs 10 and 11 away from the front face 8.

I claim:

1. A tie-knot holder comprising a resilient and transparent Y-shaped member with two flexible wing portions designed to be received in the sides of a collar and a depending portion, a resilient wire carried by the member and having its ends secured to the member, said wire having leaf-spring-like portions on the front face of the member for forming a hollow body for a tie knot and having a button receiving portion disposed on the rear face of the member for connecting the device to a collar button where it is supported in proper position, said member having openings in its depending portion for slidably receiving the wire lengths that connect the leaf springs with the button receiving portion.

2. A tie-knot holder comprising a resilient and transparent Y-shaped member with two flexible wing portions designed to be received in the sides of a collar and a depending portion, a resilient wire carried by the member and having its ends secured to the member, said wire having leaf-spring-like portions on the front face of the member for forming a hollow body for a tie knot and having a button receiving portion disposed on the rear face of the member for connecting the device to a collar button where it is supported in proper position, said member having openings for slidably receiving the wire portions that connect the leaf spring portions with the button receiving portion, the button receiving portion increasing the effective length of the spring portions to make the latter more resilient.

3. A tie-knot holder comprising a Y-shaped member formed from a resilient and transparent material, the flexible wings of the Y being received in the collar, and a spring wire having its ends secured to the member and curved leaf-spring portions extending from the secured ends over the front face of the depending portion of the member, said depending member portion having openings for slidably receiving the wire portions disposed at the free ends of the leaf-

springs, said wire having a looped portion on the rear face of the member for engaging with a collar button, the looped portion being enlarged for receiving a collar button and the enlarged portion being disposed close to the openings in the member and acting as a stop for limiting the swinging of the leaf-springs above the front surface.

4. In a tie-knot holder, a Y-shaped member 10 made of transparent resilient material, the wings of the Y being receivable in the collar and the depending portion receiving a tie knot, the top edge of the member disposed between the wings being elongated to provide sufficient space to receive tie portions, a resilient wire having its ends anchored to the member and two parallel portions extending from the ends and lying in front of the member, said depending portion having openings for slidably receiving the parallel wire portions, the portion of wire extending in back of the member having a large button-receiving portion and a small portion for receiving the button shank.

5. A tie-knot holder comprising a Y-shaped member 25 formed from a resilient transparent material, the wings of the member being receivable in the collar, and means for supporting the member on a collar button, said means comprising a resilient wire with ends secured to the member and parallel leaf-spring portions extending downwardly from the ends over the front face of the depending portion of the member, said depending portion having openings for slidably receiving the free ends of the leaf-spring portions, the remainder of the wire being formed into a loop for receiving a collar button and a reduced recess for receiving the shank of the button or the threads securing the button to the collar.

6. A tie-knot holder comprising a Y-shaped member 40 formed from a resilient transparent material, the wings of the member being receivable in the collar, and means for supporting the member on a collar button, said means comprising a resilient wire with ends secured to the member and parallel leaf-spring portions extending downwardly from the ends over the front face of the depending portion of the member, said depending portion having openings for slidably receiving the free ends of the leaf-spring portions, the remainder of the wire being formed into a loop for receiving a collar button and a reduced recess for receiving the shank of the button or the threads securing the button to the collar, the portions of the wire loop disposed adjacent to the openings being bent outwardly at right angles to lie parallel with the rear face of the depending member to act as stops for limiting the flexing of the leaf-springs away from the front face of the member.

SEVERIN B. BANKSON.
